CLAIM

The ornamental design for a shoe as shown and described.

DESCRIPTION

FIG. 1 is a left side view of a shoe showing the claimed design;

FIG. 2 is a right side view thereof;

FIG. 3 is a front view thereof;

FIG. 4 is a rear view thereof;

FIG. 5 is a top view thereof;

FIG. 6 is a bottom view thereof; and,

FIG. 7 is a top perspective view thereof.

The broken lines in figures and the area(s) within the broken lines show portions of the shoe that form no part of the claimed design.

1 Claim, 7 Drawing Sheets

Related U.S. Application Data

a continuation of application No. 29/757,693, filed on Nov. 9, 2020, now Pat. No. Des. 965,962.
